CURTAIN HANGER

Filed Sept. 14, 1922

By his Attorneys
Cooper, Kerr & Dunham

UNITED STATES PATENT OFFICE.

ELMER R. ROBERTSON, OF NORTH CONWAY, NEW HAMPSHIRE.

CURTAIN HANGER.

Application filed September 14, 1922. Serial No. 588,124.

This invention relates to curtain hangers. More specifically it relates to hangers adapted to support curtains of the roller type and has for one of its objects to provide a 5 novel form of hanger by virtue of which the curtain will hang in desired position and will not be marred or injured when rolled or unrolled.

Curtain hangers for roller curtains, as 10 at present constructed, are open to objection in that if the shade or curtain is not pulled at the center of its bottom edge and in a direction at right angles to the axis of rotation of the roller, the shade or curtain will 15 extend beyond the end of the roller and rub the supporting bracket upon being raised or lowered. This causes the rubbing edge or edges of the curtain to become marred and eventually demolished. Furthermore, the curtain so supported does not 20 always hang in the position desired, i. e., with its opposite edges substantially vertical.

In accordance with my invention, I provide 25 a curtain hanger which overcomes the objections above noted and possesses other advantages and objects which will appear as the invention is hereinafter disclosed.

Referring to the drawings which illustrate 30 what I now consider a preferred form of the invention,

Fig. 1 is a front elevation of a curtain hanger with a roller curtain mounted therein.

Fig. 2 is a side elevation of one of the 35 ends of the bracket, looking in the direction of the arrow A in Fig. 1.

Figs. 3 and 4 are detail sections taken substantially on the lines 3—3 and 4—4, respectively, of Fig. 1, the stud or pivot 26 being shown in Fig. 4 in a position rotated 90 degrees about its axis from the position shown in Fig. 1, for clarity in illustration.

Fig. 5 is a detail rear elevation of a part 45 of the bracket at the middle portion.

Fig. 6 is a view similar to Fig. 4 but illustrating a modification.

The curtain hanger illustrated comprises a bracket provided with spaced ears for 50 receiving the pivots of a curtain roller, and means for pivotally connecting the bracket

to a support for oscillation about an axis substantially at right angles to the vertical plane containing the axis of rotation of the curtain roller.

The bracket is shown as comprising a channel-shaped member 10 (Figs. 1, 4 and 5) which slidably supports strips 11 and 12 which telescope with said member 10. The strip 11 terminates in an ear 13 (Fig. 2), bent at right angles to the strip 11 and having the usual slot 14 to receive the flat spindle 15 of the usual shade roller 16. The latter is preferably of the usual spring and pawl type for rolling the shade or curtain 17 up when the pawls are released by a jerk, and in which the pawls operate to hold the curtain, against the action of the spring (not shown) within the roller, in any desired position. Such roller curtains 18 are well known and no further description or illustration is needed in this respect. The strip 12 terminates in an ear 18 (Fig. 3), bent at right angles to the strip 12, and having the usual hole 19 in which the spindle 20 of the roller 16 is journaled for rotation. The strips 11, 12 may be adjusted longitudinally of the member 10 to fit shades of various widths and the parts may be held in adjusted positions by means of set 75 screws 21, 21 each of which is screw-threaded into the member 10 in a position to engage a corresponding one of the strips 11, 12.

The means above referred to comprises the 80 following now preferred structure. The bracket 10 is pivotally connected to an attaching member 25. A plate 23 is tightly gripped in and preferably at the middle of the channel member 10 (Figs. 4 and 5). If 85 desirable this connection between the members 10 and 23 may be made more secure by soldering, brazing, riveting or otherwise. The plate 23 has secured thereto a sleeve or journal 24 which projects forwardly therefrom. The attaching member is shown provided with a stud or spindle 26 which is journaled in the sleeve 24 and may be upset at 27 to hold the parts together.

If the hanger is to be used in connection 90 with a window, the attaching member 25 may be shaped at its upper portion as indi-

cated in Fig. 4, to fit over the upper horizontal rail 22 of the window frame and, if desirable, to be secured thereto by means of a nail 28.

- 5 It will be seen that the curtain roller 16 is not only rotatable about its longitudinal axis but is oscillatable about the axis of the pivotal connection 24-26, the last named axis being preferably at right angles to the 10 vertical plane containing the axis of rotation of the roller, and also substantially midway between the ears 13, 18. By virtue of this construction the roller 16 will assume a position in which its longitudinal axis is 15 at right angles to the direction of pull on the curtain, whether such pull be vertical, as shown at X in Fig. 1, or at any one of various angles to the vertical, two being illustrated by way of example at Y and Z. 20 The same relationship between the axis of rotation of the roller and direction of pull of the curtain will exist, even though the pull may be exerted at some portion of the curtain other than the middle of the bottom 25 edge. In other words, the tension on the shade or curtain 17 is always uniformly distributed and the shade will roll evenly at all times and neither of its side edges will engage or rub either of the ears 13, 18 of the 30 bracket. Furthermore, in view of the fact that the pivotal axis 26 is substantially midway of the ears 13, 18 the shade will normally hang vertically, in any of its positions of adjustment, and with its side edges vertical. 35 The curtain hanger may be modified and improved in various respects without departing from the scope of the invention as defined in the appended claims. For example, the upper part of the attaching member 25 may be constructed as shown in Fig. 40 6 in which the part 101 is hinged at 102 to the remainder of the attaching member and is movable from the position shown in full lines to that shown in dotted lines and vice versa. If the building, of which the 45 window frame forms a part, has not been plastered before the attaching member 25 is mounted, the latter may be secured to frame member 22 with the part 101 in the dotted line position. If the building has been plastered, the member 25 may be mounted as indicated in full lines in Fig. 6.

If desirable, means may be provided for preventing the roller 16 from rocking back and forth, except when the curtain is manually operated, and to bias or restore the roller to horizontal position after the curtain has been operated. Such means may assume the form illustrated in which a leaf 50 spring 35 is gripped or secured (by solder, weld or rivets if necessary) at its middle portion in an offset 36 in the member 25; and engages at its opposite ends the upper edge of the channel member 10.

65 I prefer to construct the various parts of

my curtain hanger herein disclosed of suitable metal, although other material may be employed, at least for some of the parts.

The construction, operation, and advantages of curtain hangers embodying my invention will now be apparent to those skilled in the art in view of the foregoing description. As stated above, the specific form illustrated may be altered and modified in various respects without departing from the scope of the invention defined in the appended claims.

What I claim is:—

1. A curtain hanger comprising in combination, a bracket provided with spaced ears for receiving the pivots of a curtain roller, means for pivotally connecting said bracket to a support for oscillation about an axis substantially at right angles to the vertical plane containing the axis of rotation of the curtain roller, and resilient means for biasing the bracket to a position in which the axis of rotation of the curtain roller is horizontal.

2. A curtain hanger as set forth in claim 1 in which means are provided whereby the ears may each be adjusted longitudinally of the bracket to adapt the hanger for use in connection with curtains of different widths.

3. A curtain hanger comprising in combination, a bracket provided with spaced ears for receiving the pivots of a curtain roller, said ears being each adjustable longitudinally of said bracket, means for holding said ears in adjusted position with respect to said bracket, an attaching member adapted to be connected to a support, means pivotally connecting said attaching member and bracket whereby the latter may be oscillated about an axis substantially midway of said ears and substantially at right angles to the vertical plane containing the axis of rotation of the curtain roller, and a leaf spring secured at its middle portion to said attaching member and engaging at its opposite ends the said bracket on opposite sides of said axis of oscillation.

4. A curtain hanger comprising in combination, a bracket provided with spaced ears for receiving the pivots of a curtain roller, an attaching member adapted to be secured to the frame of an opening, and means pivotally connecting said bracket to said member for permitting said bracket to assume different positions about a normally horizontal axis in response to forces exerted in various directions to manipulate the curtain, said means constituting the sole support of said bracket, and said bracket being at all times free to assume different positions about said normally horizontal axis.

5. A curtain hanger comprising in combination, a bracket provided with spaced ears for receiving the pivots of a curtain roller, and means comprising a pivot for pivotally connecting said bracket to a support for os-

cillation about an axis substantially at right angles to the vertical plane containing the axis of rotation of the curtain roller, said last mentioned pivot constituting the sole support of said bracket, and said bracket being at all times free to assume different positions about said first mentioned axis.

5 in which means are provided whereby the ears may each be adjusted longitudinally of the bracket to adapt the hanger for use in connection with curtains of different widths.

10 In testimony whereof I hereto affix my signature.

6. A curtain hanger as set forth in claim

ELMER R. ROBERTSON.
